UNITED STATES PATENT OFFICE.

PETER J. FITZGERALD, OF HYDE PARK, AND DAVID F. BARRY, OF BOSTON,
MASSACHUSETTS.

CAR-HEATER.

SPECIFICATION forming part of Letters Patent No. 499,017, dated June 6, 1893.

Application filed March 2, 1893. Serial No. 464,401. (No model.)

To all whom it may concern:

Be it known that we, PETER J. FITZGERALD, of Hyde Park, in the county of Norfolk, and DAVID F. BARRY, of Boston, in the county of 5 Suffolk, State of Massachusetts, citizens of the United States, have invented certain new and useful Improvements in Car-Heaters; and we do hereby declare the following to be a full, clear, and exact description of the invention, 10 such as will enable others skilled in the art to which it appertains to make and use the same.

Our invention relates to heaters designed especially for use in connection with cars for 15 street railways, and has for its object the production of a heater, and its accessories, of comparatively simple and cheap construction, by which any desired degree of heat may be generated, and which is designed to be placed 20 in ordinary street railway cars, during the building of same, or after completion, without modifying the construction of any of the parts.

Our invention consists in the means here- 25 inafter described whereby a common source of heat is utilized to raise the temperature of the air for heating purposes and to generate steam from a body of water, and whereby the combined heat of the heated air and from the 30 steam is mingled and discharged through outlets common to both into the interior of the car.

It further consists in means for regulating the supply of air to be heated; in the peculiar 35 arrangement of the air and steam conveying pipes and in other details of construction all of which will fully and clearly appear from a reading of the following description taken in connection with the accompanying drawings

40 which form a part thereof, and in which—

Figure 1, illustrates in perspective view a car for street railways, a portion of the side thereof being broken away to show portions of our heater in position. Fig. 2 is a vertical 45 longitudinal section of the car a portion of the seat being removed to show the heater proper and the radiators for discharging hot air. Fig. 3 is a vertical central longitudinal section of the heater and its accessories in- 50 cluding the oil supply devices, before the same have been placed in the car; Fig. 4 a detail

of a portion of the casing showing different positions in full and dotted lines of the means for regulating the admission of air to the heater; and Fig. 5 is a detail, taken on line 55 $x-x$ of Fig. 1, of the means for discharging when desired the hot air outside of the car.

Like letters and figures of reference denote corresponding parts in the several figures of the drawings.

The reference letter A denotes the car, which as shown, is of the common type for street railways, and to which the heater is adapted to be applied.

We propose to place the several parts of 60 the heater under one of the seats B, although if desired the parts may be duplicated and placed under both seats.

In or on the roof of the car is arranged a tank or receptacle C for holding hydro-carbon 70 oil or other liquid for supplying the burner presently to be described. This tank is formed preferably of a metallic tube closed at both ends and provided with an opening c for filling the tank, the same being closed by 75 a cap or cover c'.

d is the supply pipe which opens into the bottom of the tank and leads to the burner.

At the point of connection of the tank and supply pipe, the latter is flared outwardly to 80 form a conical seat for the inner end of a screw plug valve d' which is raised and lowered by turning the thumb screw d² thereon for regulating the supply of oil to the burner. The pipe d is also provided with another valve 85 d³ which is located in said pipe near the top of the car and readily accessible to a person inside, and by this means the supply of oil may be instantly regulated even when the car is in motion.

Midway of the length of the car is a casing 90 e within which is arranged the burner and from which are led the pipes for supplying the heated air and steam. This casing and the pipes are as before stated placed beneath 95 the seat, and are entirely within the car and consequently all of the heat generated by radiation is communicated to the interior, and not to the outer atmosphere as would be the case where the heater is placed beneath or at 100 any other point outside of the car.

Access to the interior of the casing is per-

mitted through a suitable door in the seat, and through a door e' in the front of the casing, which is provided with a locking latch e^2 .

In the upper end of the casing is a partition f which separates the casing into two compartments $f' f^2$, the upper one f' , constituting a water chamber which may be filled through the opening f^3 from an overhead tank located in the top of the car, or from the side of the car, or from any other place desired. The partition is centrally raised or arched to provide a concave heating surface for the burner which latter is located in the chamber f^2 immediately below said partition. Extending downward from this partition is an annular deflecting plate g which terminates at a point a little above the bottom of the casing and forms a reverberatory chamber and serves to confine the air to be heated to the burner before the same passes to the points of discharge.

At each side of the casing and communicating with the interior of the chamber f^2 are hot air pipes or flues h which convey the heated air to the registers i which latter are located at each end of the car and may be provided with any suitable means for regulating the discharge of hot air therefrom. These pipes h are preferably offset at h' to increase the draft of hot air, and for another purpose presently to be explained. Air is admitted to the heater from the under side of the car through a section of pipe j which is connected to the bottom of the casing and is led through the floor of the car. The inflow of air is regulated by a perforated cap j' which is conically shaped and fits within the pipe j the sides being formed with slots or incisions j^2 to give the same a yielding pressure against the wall of the pipe to retain it in the desired position. Air is admitted through perforations j^3 and is deflected downward before its ascension to the burner by the flanged top j^4 , the object being to divide the air to be heated. The admission of the air is regulated by raising and lowering the cap to present more or less of the perforations above the bottom of the casing to increase or diminish the inflow of the air. On the under side of the top j^4 are lugs or shoulders j^5 which by contact with the bottom of the casing prevent the cap from being lowered sufficiently to prevent any inflow of air, and thus the pipe j is at all times opened and an ingress of air continually established.

We provide ready means for discharging the heated air outside of the car in the event of the inner temperature thereof becoming too high, as follows: The numeral 1 represents a pipe which is let into the hot air pipe and is carried to any point outside of the car, preferably above the line of the hot air pipe, where it terminates in a grating 2. Within this pipe is a damper 3 preferably of the rocking type which is arranged on a lever 4 the upper end extending above the pipe and fulcrumed on a lug 5. The upper end of the lever is con-

nected to a rod 6 which is passed through the seat and terminates in a suitable handle 7, which upon being pulled outward opens the damper and permits the discharge of the hot air through the pipe and grating into the outer atmosphere. By this means the temperature of the car is under full control and can be readily regulated at all times.

In the upper end or top of the casing at each side thereof are sections of pipes k which communicate with the water chamber and serve to convey the steam generated from the heated water. Connected to these sections k by suitable couplings k' are the radiating pipes l, l , which are let into the air pipes at each side of the casing at the offsets h' in the latter pipes. Return pipes $l' l'$ connect the pipes l and are preferably led into the water chamber below the water level thereof. The sections k and pipes l, l' carry the steam generated by the body of water within the chamber f' and furnish heat by radiation; which added to the heated air generated by the burner is discharged through the radiators at each end of the car as before stated. In this manner a single burner performs the double function of heating both the air in the lower chamber and the water in the upper chamber, and these sources of heat being combined and discharged through common channels the result is a heat sufficiently intense to raise the temperature in a car to the desired extent even under the most unfavorable conditions of cold.

In operation, the tank and water chamber are supplied with sufficient quantities of oil and water for a predetermined number of trips. The burner is then ignited and the air flowing into the casing is quickly heated to a very high degree of temperature. The hot air after being confined for a short period is carried downward and around the deflecting plate and upward and through the hot air pipes to the registers at each end of the car. The heat of the burner also at the same time raises the temperature of the water in the water chamber until steam is generated, which passes from said chamber through the pipes located within the hot air pipes, and the heat radiating from the steam pipes mingling with the hot air from the burner passes out through the radiators as before stated.

By means of the devices hereinbefore described, the heat generated is under the complete control of the operator. Both the supply of oil to the burner and the air to be heated may be easily and quickly regulated; and the air when heated can be discharged in any desired quantity both inside and outside of the car at will.

As before stated our heater is applicable to any type of street railway car, and may also, if desired, be employed advantageously on steam railway cars, steam boats and the like.

The several parts constituting our heater are comparatively simple in construction and may be cheaply made, and the cost incidental

to operating the heater is confined to the hydrocarbon oil or other liquid consumed.

We propose to employ in connection with the heater a hydrocarbon oil or similar burner in which the combustion is complete and consequently no perceptible odor is discharged within the car with the heated air, and we are enabled to dispense with the usual means employed for carrying off the products of combustion of the burners heretofore employed. If it should be found that in starting the burner any odor is generated, the impregnated air may, by the means hereinbefore described, be discharged outside the car until the retort is heated to a sufficient degree to cause a thorough vaporization of the oil and a complete combustion, after which the pure air is allowed to enter the car.

Having now described our invention and the manner in which the same is to be performed, what we claim, and desire to secure by Letters Patent, is—

1. In a heating apparatus, the combination, of a burner, a casing surrounding said burner, having an inlet at its bottom, and means for regulating the inflowing current of air, a plate in the casing surrounding the burner and forming a reverberatory chamber, and hot air pipes communicating with the interior of the casing for conveying and discharging the heated air substantially as described.

2. In a car heater, the combination of a burner, a casing surrounding said burner having an upper water chamber and a lower air chamber, an inlet for the air, a plate surrounding the burner forming a reverberatory chamber, hot air pipes communicating with the interior of the air chamber, steam pipes communicating with the interior of the water chamber and located within the hot air pipes, and outlets for the heated air, substantially as described.

3. In a car heater, the combination of a cas-

ing located within the car, a partition separating said casing into an air chamber, deflecting plates depending from said partition, a burner within the air chamber, an inlet for the air, pipes leading from the air chamber for conveying and discharging the heated air, steam pipes leading from the water chamber into the hot air pipes, and outlets for the heated air, substantially as described.

4. In a car heater, the combination of a casing located within the car, a burner within the casing, pipes for conveying and discharging the heated air, and an air inlet in the bottom of the casing communicating with the outer atmosphere, and a device for regulating the admission of the air consisting of a perforated cap fitting within said inlet and adapted to be raised and lowered to present more or less number of perforations above the bottom of the casing, substantially as described.

5. In a car heater, a device for regulating the supply of air to the burner, consisting of a cap movable in the inlet pipe, having the described slots and perforations in the sides thereof, an imperforate flange top, and lugs depending from the flange, substantially as and for the purpose set forth.

6. In a car heater, and in combination with a hot air conveying pipe, a register for discharging the hot air within the car, a pipe leading from the hot air pipe to a point outside the car, a rocking damper in said pipe, a lever on the damper and a rod connecting said lever and adapted to be operated inside of the car, substantially as and for the purposes set forth.

In testimony whereof we affix our signatures in presence of two witnesses.
